DEVICE FOR USE IN REFINISHING FULLING
MILL ROLLS

Bryan S. Robinson, Warren, Maine

Application December 9, 1940, Serial No. 369,330

4 Claims. (Cl. 142—40)

My present invention relates to portable devices particularly adapted for temporary installation within fulling mills for use in relagging the rolls.

While my invention may be employed for other uses, its novel features and advantages may be best illustrated by considering the problems involved in servicing fulling mills. In fulling mills there are two pairs of wooden rolls controlling the feed of the cloth through the mill, with each pair being mounted on a common shaft and being rotated oppositely to the other pair. When these rolls become uneven they must be refinished in order for the mill to operate properly, and standard procedure has been to take down the mill sufficiently to permit the heavy rolls to be removed and transported to the machine shop for turning in a lathe. The rolls may be quickly and easily refinished after their removal, but the time required to remove and replace the rolls results in a substantial loss of productive capacity of the mill.

This problem has been recognized and some fulling mills have been designed to reduce the labor necessary to remove the rolls. In such mills it is possible to bring the rolls into an exposed position without completely removing them to permit their treatment by a lathe supported on the floor exteriorly of the fulling mill, but even with such mills, service is both difficult and expensive.

In accordance with my invention I am able to minimize the expense of this phase of fulling mill maintenance. I accomplish this result by means of a portable device adapted to be supported within the fulling mill in predetermined relation to a pair of rolls. The device includes a support slidably carrying a base having an adjustable cross slide on which I mount a pair of rotatable cutters. I space the cutters so that each may have an operative position anywhere between a point adjacent a mill wall and a position common to the other. By this construction, I am able to refinish a pair of rolls without moving the device while ensuring the adaptability of my invention to all types of fulling mills. The cutters are driven at high speed by an electric motor which may be quickly detached from the device in order to decrease its weight sufficiently to permit it to be readily carried from one fulling mill to the next.

In accordance with my invention after the various mills to be serviced have once been provided with cleats or other means to support the device in desired relation to the rolls, the refin-

ishing of the rolls may be quickly effected since the rolls are not disturbed.

In the accompanying drawings I have illustrated an embodiment of my invention from which its full nature and several novel features and advantages will be readily apparent.

In the drawings:

Fig. 1 is a plan view of a device in accordance with my invention.

Fig. 2 shows the device of Fig. 1 in front view.

Fig. 3 is a view partly in cross section showing its relation to a roll, and

Fig. 4 shows my device installed in a fulling mill.

15 I have indicated at 1 the top of the base of my device, and at 2 the side walls. In order to ensure rigidity I have utilized cross pieces 3 and adjacent each end of the base 1 I provide cross pieces 4 to establish compartments for slides 5 by which the overall length of the base 1 may be adjusted as required by the distance between the walls W of a particular mill M. The slides 5 may be locked in any adjusted position by set screws 6 threaded through the wall 2 constituting the front wall of the base.

20 The other or back wall 2 carries adjacent each of its ends a boss 7 to rotatably support the screw 8 having on one end a gear 9 in mesh with a gear 10 on the shaft 11 supported in yokes 12 carried by the walls 2. The shaft 11 carries a crank 13 or the like by which it may be rotated by the operator.

25 In the embodiment of my invention shown in the drawings, the top 1 of the base extends laterally of the walls 2 to present gibbs 14 engageable by the flanges 15 carried by the apron bed 16. The bed 16 carries a fixed nut 17 into which the screw 8 is threaded so that the bed 16 may be moved along the base by turning the crank 13. Set screws 5 are threaded through the front flange 15 to ensure the proper fit of the bed 16.

30 The bed 16 and the cross slide 18 are formed to establish a sliding interlock. The bed 16 is formed to establish a compartment 18' to receive the fixed nut 19 carried by the slide 18 and also to reduce weight. A screw 20 rotated by the crank 21 is threaded through the nut 19 and rotatably supported by the ends of the bed 16.

35 The cross slide 18 supports at one end a bracket B braced as at 22 having a pair of spaced bearings 23 for the shaft 24 and a pair of guards 25 for the cutters 26 carried by the shaft 24. Intermediate the bearings 23 I mount a pulley 27 on the shaft 24.

40 Adjacent the other end of the slide 18 I pro-

vide a laterally disposed support 28 braced as at 29 to support the motor 30 with its driving pulley 31 in alignment with the pulley 27. The support 28 carries a pair of spaced uprights 32 having keyhole shaped slots 33 to receive the ends 34 of the motor mount base 35. The ends 34 are slightly flattened on one side as at 34a to fit within the narrower part of the slots 33.

The motor mount base 35 carries the motor supports 36 in off-center relation. The supports 36 are slotted as at 37 to receive the bolts 38 attaching the motor 30 thereto to permit the motor 30 to be shifted relative to the base 35 as required.

By this construction it will be apparent that the motor 30 may be quickly installed or removed by positioning it so that the ends 34 may be inserted in or withdrawn from the slots 33 while at other times the motor is locked in place although free to pivot. In Figs. 1 and 4 I have exaggerated the position of the motor relative to its supporting means but it will be appreciated that the off-center relation of the supports 36 to the base is only sufficient to ensure the weight of the motor being off-center to maintain the belt 39 taut without danger of being worked forwardly by its pull.

In practice when the motor is installed it is rocked forwardly to permit the belt 39 to be positioned over the pulleys 27 and 31 and is then brought back to bring the belt under tension.

Before devices in accordance with my invention are used, cleats 40 or other suitable supporting means are attached to the walls of a fulling mill. While in some mills the supporting means may be permanently attached to the walls W in other mills this is not possible. For that reason I have shown in Fig. 4 the cleats 40 carried by mounts 41 that may be bolted to the walls W through established bolt receiving apertures. Preferably the cleats 40 are formed with ribs 42 to enter the slides 5 to anchor the device in position. As will be apparent from the drawings, the cleats are positioned so that the device may be supported with its shaft 24 in horizontal alignment with either the shaft 43 or 44 for the rolls 45 and 46, respectively.

When a device is thus installed the mill is operated to rotate the rolls and the rapidly rotating cutters are then moved across their faces. The cutters 26 are rotated at high speed, 7000 R. P. M. for example, and because of the difference in the direction of rotation of the rolls 45 and 46 I have provided a reversible motor with

the reversing switch indicated at 47 so that the cutting action may be reversed when the device is moved from one set of cleats to the other.

I employ two cutters 26 and these are spaced to ensure the adaptability of my device to all types of fulling mills. Because the motor 30 and the bed 16 and cross slide 13 are limited in their travel on the base 1 by the walls W, I space the cutters 26 so that they may have operative positions adjacent the walls W. As shown in Figs. 1 and 2 the spacing of the cutters 26 is such that they both travel through a substantial common zone so that as one cutter 26 is brought into operative relation with one roll, the other cutter 26 may still be in an inoperative position. This relation is desirable as it ensures the adaptability of my device to all mills.

It will be appreciated that while it is desirable to have my devices of minimum weight, I have been able to accomplish this result without loss of essential rigidity so that my invention is well adapted for the efficient refinishing of rolls in fulling mills.

What I therefore claim and desire to secure by Letters Patent is:

1. A portable device to be attached to the walls of fulling mills for use in refinishing pairs of axially spaced rolls mounted therein, said device comprising a bed, a cross slide adjustably mounted on said bed, roll refinishing means mounted on said slide, a base slidably supporting said bed, and being formed with an open compartment at each end, and a base supporting slide positioned in each of said compartments.

2. The device of claim 1 in which pairs of horizontally aligned members are carried by the mill walls in predetermined relation to each pair of rolls and the base supporting slides and the members include complementary interengaging portions.

3. The device of claim 1 in which pairs of horizontally aligned members including upwardly disposed flanges are carried by the mill walls in predetermined relation to each pair of rolls and the base supporting slides comprise a rectangular frame receptive of the flanges.

4. The device of claim 1 in which said base comprises top, front and back walls, cross members intermediate said walls bracing said base and defining a compartment adjacent each end of said base, and a base supporting slide in each of said compartments.

BRYAN S. ROBINSON.
